UNITED STATES PATENT OFFICE.

JULIEN A. BRIED, OF SAN FRANCISCO, CALIFORNIA.

BLUE-PRINTING FRAME.

No. 867,698.

Specification of Letters Patent.

Patented Oct. 8, 1907.

Application filed September 27, 1906. Serial No. 336,514.

To all whom it may concern:

Be it known that I, JULIEN A. BRIED, a citizen of the United States, residing at San Francisco, in the county of San Francisco and State of California, have 5 invented new and useful Improvements in Blue-Printing Frames, of which the following is a specification.

This invention relates to photographic printing frames for printing from flexible clichés, such as tracings, films, or the like, the object of the invention being 10 to provide an improved construction of frame in which there will be no possibility of breakage of glass, which can be operated quickly, which will dispense with the use of felt or other padding, and which will be lighter and easier to handle than frames of prior construction.

15 In the accompanying drawing Figure 1 is a perspective view of the frame; Fig. 2 is a longitudinal section through the tension roller; Fig. 3 is a detail perspective view, partly in section on the line 3—3 of Fig. 2, showing the position of the pawl and ratchet device for 20 tightening the roller, when in use.

Referring to the drawing, 1 indicates a skeleton frame of wood or other suitable material, having the end pieces 2. Secured to said end pieces are the ends of an arched or convex base or foundation 3, preferably 25 of sheet metal, as aluminium. Secured to one end of said arched base is the end of a sheet 4 of thin celluloid, translucent, and preferably transparent. The other end of said sheet is secured to the circumference of a roller 5 carried by a shaft 6. Said shaft passes loosely 30 through the ends of the roller, and a spiral spring 7 surrounds said shaft, one end thereof being secured to the shaft and the other end to the end flange 8 of the roller. Upon the shaft outside the roller are secured at one end a ratchet wheel 9 and a handle 10.

35 The sensitive paper and the original or flexible negative having been laid upon the base, the celluloid sheet is laid over the same by means of the roller until the shaft 6 enters sockets 11 formed in brackets 12 secured to the frame. Latches 13 are then caused to engage 40 lugs 14 on the brackets, thus retaining the shaft in position in the sockets. The operator then turns the handle transmitting a rotary movement to the roller through the interposed spring, so that thereby tension is applied to the celluloid sheet, causing it and the underlying 45 sheets to lie very close to each other on the convex base. As the shaft is turned to energize the spring, a pawl 15 secured upon one of the brackets engages in succession the teeth of the ratchet wheel 9 and prevents the return of the shaft. When the shaft has been turned to provide 50 sufficient tension upon the celluloid sheet, the apparatus is ready for exposure. To release the shaft,

it is only necessary to remove the pawl from the ratchet wheel, and then disengage the latches from the lugs. The celluloid sheet is then wound up on the roller, and the original and print removed.

55

The advantages of this construction over prior forms of photographic printing frames for blue printing and the like are that, no glass being used, the risk of loss through breakage of glass is eliminated; the frame can be arranged for exposure and opened in a small fraction 60 of the time required with some prior frames; the use of felt or other padding is no longer required; and the device is lighter and more easily handled than certain printing frames of the old style.

60

I claim:—

65 1. In a photographic printing frame, the combination of an arched or convex smooth base or foundation, a sheet of translucent flexible material secured at one end to one end of said arched base, and means for securing the other end of said sheet at the other end thereof and for drawing the sheet tight over the base, substantially as described.

70 2. In a photographic printing frame, the combination of an arched or convex smooth base or foundation, a sheet of translucent flexible material secured at one end to one end of said arched base, and means for securing the other end of said sheet at the other end thereof and for drawing the sheet tight over the base, comprising a roller to which the sheet is secured, a shaft therefor, a spring connecting the roller and shaft, and means for turning said shaft, substantially as described.

75

75 3. In a photographic printing frame, the combination of an arched or convex smooth base or foundation, a sheet of translucent flexible material secured at one end to one end of said arched base, a roller to which the other end is secured, a shaft for the roller, a coiled spring around the shaft connected thereto and to the roller, sockets for the shaft at the other end of the base or foundation, and means for turning the shaft in the sockets to wind up the spring, and apply tension to the sheet, substantially as described.

80

85 4. In a photographic printing frame, the combination of an arched or convex smooth base or foundation, a sheet of translucent flexible material secured at one end to one end of said base, a roller to which the other end is secured, a shaft for said roller, a coiled spring around the shaft connected thereto and to the roller, sockets for the shaft at the other end of the base or foundation, means for removably securing the shaft in the sockets, and means for turning the shaft in the sockets to wind up the spring, and apply tension to the sheet, substantially as described.

90

95 5. In a photographic printing frame, the combination of an arched or convex smooth base or foundation, a sheet of translucent flexible material secured at one end to one end of said base, a roller to which the other end is secured, a shaft for said roller, a coiled spring around the shaft connected thereto and to the roller, sockets for the shaft at the other end of the base or foundation, means for turning the shaft in the sockets, and means for holding the roller in the position to which it is turned, substantially as described.

100

105

110

6. In a photographic printing frame, the combination of an arched or convex smooth base or foundation, a sheet of translucent flexible material secured at one end to one end of said base, a roller to which the other end is secured, a 5 shaft for said roller, a coiled spring around the shaft connected thereto and to the roller, sockets for the shaft at the other end of the base or foundation, means for turning the shaft in the sockets, and means for holding the roller in position to which it is turned, said means comprising a 10 ratchet wheel carried by the roller and a pawl carried by

the frame and adapted to engage said ratchet wheel when the shaft has been moved into said sockets, substantially as described.

In testimony whereof I have hereunto set my hand in the presence of two subscribing witnesses.
